UNITED STATES PATENT OFFICE

159,154

POWER CYCLE

Fred H. Johnson, Pleasant Ridge, Mich.

Application July 23, 1949, Serial No. 4,090

Term of patent 14 years

(Cl. D90—8)

To all whom it may concern:

Be it known that I, Fred H. Johnson, a citizen of the United States, residing at Pleasant Ridge, county of Oakland, State of Michigan, have invented a new, original, and ornamental Design for a Power Cycle, of which the following is a specification, reference being had to the accompanying drawings, forming part thereof.

Fig. 1 is a perspective view of a power cycle showing my new design;

Fig. 2 is a side elevational view; and

Fig. 3 is a top plan view thereof.

The dominant features of my design reside in that portion shown in full lines in the drawing.

I claim:

The ornamental design for a power cycle, substantially as shown and described.

FRED H. JOHNSON.
